UNITED STATES PATENT OFFICE.

HENRY G. VOIGHT, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

LATCH MECHANISM.

No. 833,266.

Specification of Letters Patent.

Patented Oct. 16, 1906.

Application filed July 19, 1905. Serial No. 270,306.

To all whom it may concern:

Be it known that I, HENRY G. VOIGHT, a citizen of the United States, residing at New Britain, Hartford county, State of Connecticut, have invented certain new and useful Improvements in Latch Mechanism, of which the following is a full, clear, and exact description.

My invention relates to improvements in locks and latches, and particularly to a means for holding back the latch-bolt while the door is open, so that no part of the latch-bolt will protrude sufficiently to admit of anything catching thereon and becoming torn. It not infrequently happens that the wearing-apparel of persons in passing an open door is caught and torn by the protruding latch-bolt. By my invention this danger is entirely obviated.

In the accompanying drawings, Figure 1 is a plan view, partly in section, of a portion of a lock or latch fitted with my improved holdback mechanism. Fig. 2 is a view of the parts shown in Fig. 1 in full, looking down relatively to the position assumed in Fig. 1. Fig. 3 is a fragmentary view of certain parts shown in Fig. 1, the holdback mechanism being shown in a different position. Fig. 4 is a sectional detail view showing the operating member.

A is a knob.

B is a latch bolt or head.

C is an end plate through which the latch-bolt B is capable of reciprocation.

D is a latch-slide.

D' is a connection between the latch-slide and the bolt B.

E is a roll-back.

F is a spring arranged to normally project the bolt B outwardly.

G is a retaining device arranged to engage with a suitable stop shoulder or projection on the latch-bolt B when said retaining device is in one position and be freed thereof when in another position. This retaining device is preferably formed of spring metal secured at one end G' to a part of the end plate C, while another part G² is arranged to engage the bolt, while still another part G³ is arranged

to be engaged by the operating member H. 50 This operating member is preferably in the form of a pin, the head of which projects laterally of the lock and is capable of movement in a line at right angles to the line of movement of the latch-bolt B. 55

J represents the stop-bead of a door-casing. The position of the operating device H is such that when the door is closed it will encounter this stop-bead J and stand in the position shown in Fig. 1, the opposite end of said operating device moving the retaining member G so as to free it from the bolt B. In this position it will be seen the bolt B may be projected freely outwardly under the influence of spring F, so that it will stand in a position 60 to engage with the keeper-plate, (illustrated conventionally at J'), such keeper-plates being well known. When the user turns the knob A and retracts the bolt B and opens the door, the operating device H assumes the position indicated in Fig. 3, and the retaining member G also assumes said position wherein it will engage the latch-bolt. K represents the shoulder engaged by said retaining member. (See Fig. 3.) In this particular arrangement it will be observed that nothing stands beyond the face-plate C on the door when the latter is open. Consequently all danger of tearing the clothes of passers-by is removed. Another and substantial advantage is that the danger of battering up the strike-plate J' when the door is closed is avoided, since the bolt B is not released until the door is practically closed, at which time said latch-bolt is released and will spring forward to engage in the recess in said strike-plate. 85

Having thus described my invention, what I claim is—

1. In a latch mechanism, a frame having a 90 plate adapted to the side of the door and another plate adapted to the edge of the door with a vertical notch at the junction between said plates, a bolt protruding through the end plate, a rotatable knob carried by the side 95 plate, operative means of connection between said knob and said bolt, means for automatically retaining said bolt when retracted by

said knob, and a projecting device guarded in said notch for releasing said retaining means.

2. In a latch mechanism, a frame having a side plate and an end plate rigid therewith, and having a notch at the end of the side plate, a spring-pressed bolt carried by said frame, means for automatically retaining the

bolt when retracted, and means for releasing said retaining means automatically, said releasing means having a portion extending into and guarded in said notch.

HENRY G. VOIGHT.
